UNITED STATES PATENT OFFICE.

HENRY R. GILSON, OF BADEN, PENNSYLVANIA.

ATTACHMENT-PLUG.

1,123,187.

Specification of Letters Patent. Patented Dec. 29, 1914.

Application filed June 27, 1913. Serial No. 776,046.

To all whom it may concern:

Be it known that I, HENRY R. GILSON, residing at Baden, in the county of Beaver and State of Pennsylvania, a citizen of the 5 United States, have invented or discovered certain new and useful Improvements in Attachment-Plugs, of which improvements the following is a specification.

The object of my present invention is to 10 provide a simple and efficient attachment plug for electrical installations, such plug being provided with a protecting casing, and constructed in such a manner that the several parts thereof may be united in a rigid 15 structure by means of a single securing member.

A further object of my invention is to 20 provide an efficient and cheaply manufactured contact post for such attachment plugs.

In the accompanying drawing, which forms part of my specification, I have illustrated an embodiment of my invention, the plug being connected to the end of an electrical conductor conduit.

Figure 1 is a side elevation of the complete plug; Fig. 2 is a bottom plan view of the disclosure of Fig. 1, the cap being removed; Fig. 3 is a central longitudinal 30 sectional view of the complete installation; Fig. 4 is a bottom plan view of the body portion of the plug; Fig. 5 is a sectional view taken on the line V—V; and Fig. 6 is a top plan view of the cap.

Like numerals are used to designate like parts in the several figures.

In the practice of my invention I provide a body block of insulation, suitably shaped for the desired installation, and provided 40 with a pair of contact clips. Extending over the clips, and protecting them against an accidental short circuit, I provide an insulation cover having holes through which contact posts of a cap may extend. Both 45 the body block and cover are provided with suitable detents adapted to be engaged by correspondingly formed detents of a casing, which covers the exposed portions of the insulating members and interlocks them 50 in such a manner that the several parts of the attachment plug may be united into a rigid structure by means of a single screw or like securing member.

Referring more particularly to the embodiment of my invention illustrated herein, the body block 1 is cylindrical, having a

groove in one side adapted to receive the conduit 2. A pair of diverging contact clips 3, 3^a are mounted in the block, and, in a central recess thereof, a nut 4 is embedded 60 in wax. The outer portion of the block is provided with an annular bead 5 on which the casing 6 rests, the continuity of the bead being interrupted by a detent 7, which fits into a correspondingly formed 65 detent or notch in said casing. The insulation cover 8 is also cylindrical and is provided with holes 9, 9^a, enlarged interiorly to receive the clips 3, 3^a, and through which hole contact posts 10 of cap 11 may be inserted to make the desired electrical connection. Between the holes 9, 9^a, a slot or groove 12 is formed, the casing 6 also having a depressed portion or groove 13 adapted to fit neatly into such cover groove, and thereby prevent relative movement of the 75 casing and cover.

The body 1, cover 8 and casing 6 are secured together by means of a screw 14, which extends through the grooved portions of the casing and cover and engages 80 the nut 4 of body 1. When the parts are thus assembled, it will readily be seen that the casing 6, which is preferably made of pressed metal, serves the double function 85 of a protection for the outer surfaces of the body 1 and cover 8, and an interlocking member between said parts.

The contact posts 10 of cap 11 are of a particular form which I find to be very 90 efficient and cheaply manufactured. Each post is of the knife blade or flat plate type and has a hook portion 15 extending laterally from one side thereof, such hook 95 affording a substantial lock when engaging the diverging clips 3. The manufacture of the posts 10 is effected by a stamp or die press, the hook portion 15 being formed by a suitable recess in the die block.

I claim as my invention:

1. In an electric attachment plug, the combination of an insulating body having a pair of contact clips mounted therein, an insulating cover adapted to protect said clips and provided with openings to receive contact posts, a casing interlocked with said body and with said cover, and a single securing means uniting said several parts into a rigid structure.

2. In an electrical attachment plug, the combination of a cylindrical insulating body having a pair of contact clips mounted

therein, an insulating cover adapted to protect said clips and provided with openings to receive contact posts, said body and cover each provided with a casing-engaging detent, and a casing provided with detents interlocking with said body and cover detents, and a single screw engaging said body through said cover and casing and thereby uniting said several parts into a rigid structure.

3. In an electric attachment plug, the combination of a cylindrical insulating body having a pair of contact clips mounted therein and provided with an annular bead 15 to receive the edges of a casing, the continuity of said bead being interrupted by a casing engaging detent, an insulating cover adapted to protect said clips and provided

with openings to receive contact posts, there being a groove between said openings, a metal casing inclosing said cover and bearing upon said bead, the edge of said casing being provided with a detent and the central portion thereof with a groove adapted to engage said bead detent and said cover 25 groove respectively, and a single screw extending through the grooved portions of said casing and cover and engaging said body thereby uniting said several parts into a rigid structure.

In testimony whereof I have hereunto set my hand.

HENRY R. GILSON.
